UNITED STATES PATENT OFFICE

154,579

DESIGN FOR A SCROLL SAW

Allen L. Atkins, Chicago, Ill.

Application March 24, 1948, Serial No. 145,328

Term of patent 3½ years

(Cl. D93—3)

To all whom it may concern:

Be it known that I, Allen L. Atkins, a citizen of the United States, and resident of Chicago, in the county of Cook and State of Illinois, have invented a new, original, and ornamental Design for a Scroll Saw, of which the following is a specification, reference being had to the accompanying drawing, forming a part thereof.

Fig. 1 is a perspective view of a scroll saw, showing my new design.

Fig. 2 is a top plan view of the same on a slightly reduced scale.

Fig. 3 is a front elevational view of the same on a slightly reduced scale.

I claim:

The ornamental design for a scroll saw, substantially as shown.

ALLEN L. ATKINS.
